7 Claims. (Cl. 299—114)

This invention relates to liquid spray nozzles of the spill type particularly for use with liquid fuel burners. The invention is concerned with the spill type of nozzle which comprises a swirl chamber into which liquid enters tangentially under high pressure, a circular discharge orifice co-axial with the swirl chamber at one end thereof, and a circular spill orifice co-axial with the swirl chamber at the opposite end thereof, this spill orifice having a diameter not less than that of the discharge orifice. The spill flow may be controlled, for example, by a restriction to flow in the spill line leading from the spill orifice. The advantage of a spill spray nozzle is that adequate atomization of the sprayed liquid takes place over a large range of spray flow rates, since the energy in the vortex is independent of the rate of discharge. Much thought has gone into the designing of spill spray nozzles to obtain the maximum efficiency and one feature of such design is the provision of a diffusing chamber behind the spill orifice where swirling motion of the spilled liquid is reduced and its kinetic energy converted into liquid pressure thus avoiding an unnecessarily large pressure drop between supply and spill lines.

My research into spill spray nozzle design leads me to think that however well the spill orifice and diffusing chamber are designed and made there is inevitably considerable loss of swirl energy in the spilled liquid. This is due to the fact that the liquid swirls at high speed over the spill orifice and diffusing chamber surfaces so that friction and viscosity absorb a considerable amount of swirl energy. Thus the conversion of swirl energy into liquid pressure cannot be very efficient. In particular this efficiency will be very low where the liquid is of a viscous nature.

The manufacture of a spill spray nozzle requires high accuracy and high surface finish of the spray orifice, spill orifice, swirl chamber, and diffusing chamber where efficiency in operation and matching of a plurality of nozzles is required. By the term "matching" reference is made to the arrangement of a set of nozzles directly connected to common supply and spill lines which will all operate at substantially similar flow rates without the employment of flow equalising devices. Such an arrangement is highly desirable for an aircraft gas turbine where a plurality of spray nozzles must be used.

Spill spray nozzles of the kind referred to operate with a central air core in the swirling liquid, this air core extending from the spray orifice through the swirl chamber into the spill orifice. For use with aircraft gas turbines it is highly desirable that air from this air core should not enter the spill line and for this purpose the spill orifice of each nozzle should include a base or baffle to prevent external air entering the spill line.

The main object of the present invention is to provide an efficient construction of spill spray nozzle of the type referred to which is of a simple nature, the number of accurately formed and highly finished components being reduced to a minimum by the substantial elimination of the diffusing chamber.

2

A further object is to provide a spill spray nozzle construction of the kind referred to by which a plurality of the nozzles may be used directly connected to common supply and return lines, all of the nozzles operating at substantially the same individual flow rates without the use of special flow equalizers. A still further object is to provide a spill spray nozzle construction of the kind referred to in which the danger of air entering the spill line is eliminated.

- 5 10 15 20 25 30 35 40 45 50 55 60 65 70
- In accordance with the present invention in a spill spray nozzle of the type referred to, the spill orifice opens rearwardly into a diametrically extending passage having a forwardly facing rear wall of which the central portion constitutes the base or baffle for the air core of the swirling liquid, the said passage having outlet openings in its two outer ends which lead to a common spill line. Preferably these outer end portions of the base wall are inclined in the sense of flow away from the central portion. By these means the provision of a diffusing chamber having an accurate highly finished surface is eliminated, the operation being that liquid passing in a swirling manner through the spill orifice is suddenly prevented from swirling as it enters the passage, conversion of the swirl energy into pressure thus being accomplished by a ram effect. Whilst this conversion cannot be said to be the most theoretically efficient it does not involve diffusing chamber losses and in fact a spill spray nozzle in accordance with this invention is found to operate at about the same efficiency as a more usual spill spray nozzle employing a diffusing chamber. The making of the diametral passage, when this is done by slotting transversely the end of a male member inter-fitted with a female member, is a more simple manufacturing operation than the making of a highly finished diffusing chamber since the passage itself need not be highly finished or of accurate dimensions. This is due to the fact that once the high velocity swirl is eliminated the flow of liquid is reduced and frictional losses are accordingly less.
- The nozzle preferably comprises a plurality of elements clamped co-axially in end-to-end relation, one element including the base of the swirl chamber and the spill orifice whilst the adjoining element includes the passage conveniently formed as a slot which is located against the outer end of the element including the spill orifice.
- A preferred embodiment of the invention for use as a spill spray nozzle in a combustion chamber of an aircraft gas turbine will now be described with reference to the accompanying drawings, in which:
- Figure 1 is a side elevation of the nozzle with one half in section and
- Figure 2 is a perspective view of one element of the burner.
- The nozzle shown comprises an annular inlet passage 11 surrounding a co-axial spill passage 12. The inlet passage 11 conducts liquid fuel to a pair of tangential inlet orifices 15 formed in the cylindrical wall 13 of a swirl chamber 14. Forwardly the swirl chamber 14 terminates in a co-axial spray orifice 16 and rearwardly it terminates in a co-axial spill orifice 17. The spill orifice is of greater diameter than the spray orifice and is formed in an element 18 which is spigoted into the element constituting the swirl chamber. There is spigoted into the element 18 a further element 19 which apart from a diametral slot 20 closes the space within the element 18 at the rear of the spill orifice 17. The diametral slot 20 has a forwardly facing rear wall comprising three flat portions namely a central portion 21 and inclined end portions 22. The element 19 is hollow and each end portion 22 has an outlet opening 23 formed therein leading into the hollow of the element which forms the beginning of the common spill line or passage

12. The central portion 21 forms the base or baffle for the air core in the swirling fuel and positively prevents air from this air core passing into the spill line 12. The width of the slot 20 is preferably substantially equal to the diameter of the spill orifice 17 and the outlet openings 23 are large enough not to present any undue restriction to flow into the spill line 12. The amount of fuel that is caused to discharge as a conical spray from the spray orifice 16 depends on control means outside the burner whereby the desired resistance to flow along the spill line is created. However, this control means is outside the scope of the present invention. The various elements which go to make up the nozzle are clamped together by means of an internal flange 24 at the forward end of an external shroud 25 by means of an internal nut 26. An external flange 27 at the base of the shroud 25 forms the means by which the whole burner is clamped to a supporting pipe 28 by means of the clamping ring 29. The pipe 28 in fact encloses the fuel supply passage 11 and liquid from this passage through holes 30 in the internal nut 26 to the space between the various burner elements and the inside of the shroud 25. Thus the supply fuel obtains access to the tangential openings 15 to the swirl chamber 14.

The dimensions of the slot 20 formed at the end of the element 19 are not critical, but it should be of the same width as the spill orifice 17 or slightly wider. A high surface finish to this orifice is not necessary since swirling motion of fuel from the spill orifice is stopped when it enters the slot and the velocity of fuel along the slot is thus comparatively slow so that frictional losses with the slot walls are not important. Thus the need for the provision of an accurately formed highly finished diffusing chamber is eliminated and is substituted simply by the formation of the slot 20 which is not critical as regards dimensions or surface finish.

The embodiment described is of course only an example of the invention and various modifications may be made particularly with regard to the formation of the diametral passage.

I claim as my invention:

1. A spill spray nozzle for connection to supply and spill lines, respectively, said nozzle comprising a nozzle body chambered to define a circular-sectioned swirl chamber tangentially ported for communication with the supply line and having at one end a central spray orifice and at its opposite end a central spill orifice of larger diameter, said body being formed beyond the spill orifice from the spray orifice with two generally parallel side walls disposed in planes parallel to and at opposite sides of the axis of the body, a bottom wall directed transversely of that axis, and a top wall generally parallel to the bottom wall but pierced centrally by the spill orifice, said side, bottom and top walls defining a transverse passage opening centrally to and receiving liquid from the spill orifice, and extending radially outwardly therefrom, and outlet ports formed in said body, opening at the ends of said passage radially outwardly of the spill

orifice, for exit of the liquid from said passage to the spill line after traversing said passage.

2. A spill spray nozzle as claimed in claim 1, wherein the said nozzle body includes one element having formed therein the base of the swirl chamber and the spill orifice, and a second element clamped to the first element in endwise co-axial arrangement having therein a diametral slot which forms the diametral passage in conjunction with the first element.

10 3. A spill spray burner as claimed in claim 2, wherein the said second element has an internal bore which is in connection with the spill line and with the ends of the diametral slot.

15 4. A spill spray burner as claimed in claim 3, wherein the width of the diametral slot is not less than the diameter of the spill orifice.

5 5. A spill spray burner as claimed in claim 4, wherein the base of the slot includes a plain central portion facing towards the spill orifice.

20 6. A spill spray nozzle as claimed in claim 5, wherein the central portion of the base of the slot is plane and transverse to the nozzle's axis, and the ends of the base of the slot are inclined in the sense of flow from the plane central portion, and the outlet ports are located in 25 such inclined end portions.

7. A spill spray nozzle for connection to supply and spill lines, respectively, said nozzle comprising a hollow shroud and annular coaxial elements therein cooperating therewith and ported to define a circular-sectioned and axially disposed swirl chamber, a surrounding supply chamber, tangentially directed supply ports admitting liquid from the supply chamber to the swirl chamber,

30 an axially disposed spill line, a central spray orifice at the outer end of the swirl chamber, and a central spill orifice of larger diameter at the inner end of the swirl chamber, one of said elements adjoining another along matching transverse surfaces located at the inner end of the spill orifice, one of said two elements being slotted diametrically in its matching surface, to define two generally transverse side walls disposed parallel to and at opposite sides of the body's axis, and a bottom wall joining the two side walls and disposed generally transverse to such axis, the slot being of a width generally corresponding to the diameter of the spill orifice, and 45 extending at its end portions beyond such diameter, these end portions being closed in by the matching member to define diametral passages, of which a surface of the matching member constitutes a top wall, and outlet ports formed in the inner of said two elements, adjacent the outer ends of said passages, and communicating with the spill line.
